A. W. HERRICK

FLYING MACHINE

Filed June 22, 1925

FIG. 1

FIG. 2

INVENTOR.
Arthur W. Herrick
BY
Victor E. Randall
ATTORNEY.

UNITED STATES PATENT OFFICE.

ARTHUR W. HERRICK, OF BATTLE CREEK, MICHIGAN.

FLYING MACHINE.

Application filed June 22, 1925. Serial No. 38,795.

To all whom it may concern:

Be it known that I, ARTHUR W. HERRICK, a citizen of the United States, residing at Battle Creek, in the county of Calhoun and State of Michigan, have invented certain new and useful Improvements in Flying Machines, of which the following description, with appended claims, taken in connection with the accompanying drawings, 10 forms a specification.

The present invention relates to flying machines and it particularly has reference to machines of the character in which motive power is supplied by the aviator through the 15 medium of a foot-lever mechanism and suitable gearing trained to operate a propeller.

A characteristic feature of the present invention is a chassis having three wheels so arranged and connected that the machine 20 will be properly stabilized while on the ground, and when at an altitude the trailer third wheel will form a rudder by which the machine may be laterally guided in its course.

25 A novel feature of the construction is a foot-lever ratchet mechanism by which dead centers are eliminated and all motive force directly applied to operate the propeller.

Another feature of importance is the provision of gas-inflated wings designed in the 30 usual manner to cut the air and form a buoying medium during flight.

An object of importance is a stabilizing device in the nature of a vertically-arranged 35 balance-wheel aligned with its periphery in the direction of flight, to minimize air resistance and to act as a power storage.

Another object of great advantage is to 40 arrange the driving mechanism whereby momentum to operate the propeller may be drawn on or curtailed while the driving mechanism is in operation, and whereby the speed of the propeller may be increased or diminished during the operation of said driving mechanism.

Still another object of the invention is to 45 so construct the pedals that their alternating movements will be equal and friction between their operating parts be reduced to a minimum.

The foregoing and other objects and advantages will be apparent to those familiar with the art to which my invention appertains.

50 In the drawings forming a part of this

specification, Figure 1 represents a side elevation of my improved flying machine.

Fig. 2 is a front elevation of the machine.

Fig. 3 is a detail modification of the shift-friction driving-mechanism and frame part. 60

Like marks of reference refer to corresponding or equivalent parts in the different views, in which A represents forward wheels connected by a common axle 1; B, a webbed rear wheel and laterally guiding rudder journaled in a fork 2 pivoted to a post 3, said fork having laterally-extending arms 4 from the extremity of which connecting links 5 engage with the ends of a cross-bar 6 mounted at the lower end of a shaft journaled in a vertical post 7, the upper end of said shaft carrying a handle 8 centrally pivoted thereto, by which means said shaft may be oscillated in the post 7, and the wheel B swayed sidewise in laterally steering the machine, the handle 8 in its swiveled connection with said shaft being also adapted to tilt an elevating and lowering tail-wing, as hereinafter set forth. 70

Between the forward wheels A, an inverted U-shaped frame C is placed in vertical position with its lower limbs engaging the axle 1, its free ends curving down and forward and forming bearings to which 80 pedal levers 9 are pivoted.

85 Diagonal braces 10 extend from near the curved end of the frame C and engage the axle 1 at its junction with the wheels A. At the ends of the axle 1, braces 11 are attached and extend laterally upward and engage the outer ends of inflatable wings D, thence extend upward and are secured to the outer ends of an upper cross-wing E, said wing E at its rear being supported by a reduced extension of the post 3. The inner ends of the wings D are stabilized by braces 12 attached to the diagonal frame braces 10. 90

95 As will be noted, the wing E crosses the entire machine and is placed in such position that it serves both as a shade and storm protector for the aviator, and its position and shape is such that it tends to stabilize the machine in a manner similar to the action of a parachute. 100

105 The wings D are provided with suitable inflating valves α for the purpose of admitting gas to buoy the machine during flight; otherwise, increased motive power would be necessary to drive the machine and hold it in suspension while being driven. 110

As shown, a cross shaft 13 extends through the sides of the frame C and at its ends carries housed ratchets, the housings 14 of which on their exterior have gear teeth 5 adapted to engage with racks 15 pivoted to the foot levers 9, and that said racks may be kept in operative contact with the housings of said ratchets, the racks operate through yokes 16 pivoted on the shaft 13.

10 The foot levers D are joined by means of a flexible connection consisting of side cords 17 and an intermediate piece of link belt 18, said belt being trained over a gear segment 19 journalled on a stud affixed to a cross girt 20 between the side members of a forked and rearwardly-curved central frame-part 21. The forward ends of the frame 21 engage the axle 1 at its junction with the frame C, the rear end of the part 20 21 being secured in a bracket 22 carried by the post 3, as shown. Between the forks of the frame 21 the post 7 is mounted, and to the rear of said post the aviator's seat 23 is placed.

25 By the provision of the flexible connections between the foot levers, as one lever is depressed the opposite lever will rise, and vice versa. The ratchets within the housings 14 are such that by depressing a foot lever motion will be imparted to the shaft 13, and through the medium of a gear 24 on said shaft communicate motion to a secondary shaft 25 through a pinion 26 on said shaft. The shaft 25 at one end is journalled 30 in a bearing attached where one of the braces engages with the U-frame C, the opposite end of the shaft being carried in a bearing 27 mounted on a shaft 28 disposed transversely to the shaft 25, said shaft 28 35 at its rear end being journalled in an offset bearing 29 of the post 7.

The shaft 25 carries a balance wheel 30 which may form a part with the pinion 26, shown in the modified form in Fig. 3. This 40 balance wheel opposite to the pinion 26 is slightly concave near its center for the purpose of clearance for a friction roller 31 carried at the inner end of a sleeve 32 longitudinally mounted on the shaft 28, but rotatable with said shaft through the medium of a spline 33 (shown in Fig. 3). The reverse side of the balance wheel is formed with a beveled race 34 against which a beveled roller 35 bears, and is for the purpose of preventing said balance wheel and its shaft from yielding longitudinally when the friction roller 31 is moved in contact with its opposite face in driving said roller and its shaft 28.

60 The sleeve 32 is longitudinally moved on the shaft 28 by means of a hand lever 36 and a trunnioned ring through which said sleeve operates, the trunnions of said ring extending through oppositely-disposed slots 65 in said lever. The object of the longitudi-

nally movable sleeve with its friction roller is to vary the speed of the shaft 28 in its relation to the driving wheel 30, as, for instance, when the friction roller 31 is moved rearwardly toward the operator and toward the periphery of the balance wheel its momentum is increased, and when moved toward the center of the balance wheel the momentum is decreased, corresponding motion being imparted to the propeller, as will be explained.

By moving the friction roller on its shaft 28 to where it enters the dished portion of the balance wheel 30, hereinbefore set forth, motion of said roller and co-operative parts 80 would be eliminated, as will be obvious.

For the convenience of the operator in regulating his speed, the hand lever 36 is made adjustable through the medium of a quadrant 38, into the notches of which a hand-latching mechanism 39 of the usual construction is adapted to operate.

Attached to the outer end of the shaft 28, a spur gear 40 meshes with a corresponding pinion (not shown) on the shaft 41 on which the propeller 42 is mounted, said shaft 41 being journalled in a bearing 43 mounted between the frame sides C.

In the modified form shown in Fig. 3, the propeller 42 is driven directly by the friction roller 31 on the propeller shaft 41 by the balance wheel 30, the means for regulating the speed of the propeller and for shifting the friction roller 31 being substantially as hereinbefore set forth. In the modified 100 form shown, a horizontal, curved frame-tie 44 connects the side members of the U-shaped frame C, and between a curved lateral extension of said tie and a correspondingly-formed bracket 45 the bevel roller 35 105 is mounted.

Referring to the mechanism for tilting the elevating and lowering wing 36: this wing extends transversely over the lateral guiding wheel B and is attached to the 110 bracket 22 by a hinge 47, and is operated by the handle bar 8. On the spindle to the handle bar a gear segment 48 is also mounted and over this segment a short link belt 49 is trained. To the ends of this belt, flexible cords 50 are attached and pass down on either side of the post 7 and under sheaves 51 journalled on said post. One of said cords is trained over a sheave 52 mounted in an opening in the post 3 below and forward of the wing 46 and fastened to a downwardly-extending bracket 53 of said wing. The other cord passes over a sheave 54 also mounted in an opening in the post 3 above the bracket 22, and is attached to an upwardly-extending bracket 55 of said wing. Obviously, tilting the handle 8 would pull on one of the cords 50 and exert a pulling strain on the wing 46 and tilt said wing on its hinged connection with the post 3 in the 120 125 130

direction of the pull, at which time the opposite cord would draw back, and vice versa.

Throughout the description of the machine I have referred to "bearings." Generally speaking, oscillating and rotary moving parts are preferably fitted with suitable ball bearings whereby all friction of the associated parts will be rendered as slight as compatible with rigidity. The framework 5 should be made up of bamboo, aluminum, magnesium, or combinations of these or other light materials.

A machine of the character described and set forth provides a neat and novel device 15 for gliding and recreation purposes not attained in the large, cumbersome and expensive planes generally in use.

Obviously, modifications other than those I have set forth might be resorted to in carrying out my invention without departing 20 from the spirit or sacrificing any of the advantages disclosed, and I therefore consider my own all such modifications and adaptations of the forms of the apparatus illustrated and described as do not depart from the spirit and scope of my invention as outlined in the appended claims.

Having, therefore, set forth my invention, what I claim as new and desire to secure by 30 Letters Patent, is:—

1. In a device of the character set forth, the combination of a chassis having three triangularly-arranged carriage wheels, two of the wheels being oppositely disposed on a 35 common axle, an inverted U-shaped frame engaging said axle intermediate its supporting wheels, a brace on either side of said frame engaging said axle near its supporting wheels, a forked supporting frame-part extending from said U-shaped frame rearward and uniting with a steering head, a fork journaled in said head in which a steering or third wheel is journaled, a seat fitted forward of said steering head mounted on said 40 forked supporting frame part forward of said seat, a steering post mounted in said steering head, and means connecting said steering wheel with said steering head whereby said wheel may be laterally adjusted.

2. In a device of the character set forth, the combination of a chassis having three triangularly-arranged carriage wheels, two of said wheels being oppositely disposed on a common axle, an inverted U-shaped framework mounted intermediate of said wheels on said axle, foot levers pivoted at the ends of said framework, a cross shaft journaled in said framework carrying a large gear and two ratchets, a link connecting a ratchet and a foot lever either side of said gear, a gear segment mounted on said chassis, a chain section trained over said gear segment and having end extensions engaging said foot levers, as and for the purpose set forth.

3. In a device of the character set forth, the combination with a chassis having three carriage wheels in triangular arrangement, two of said wheels mounted on a common axle, a framework mounted on said axle and carrying at its upper end a propeller journaled transverse to said axle, means to rotate said propeller, a standard comprising a part of said chassis aligned to the rear of said propeller, brace members extending from the ends of said axle outward and upward, a plane carried between the ends of said brace members above and to the rear of said propeller and engaging said standard centrally to its rear, a plane mounted above said axle either side of said propeller and supported at the outer ends by said members and at the inner ends by brace members on said U-shaped frame.

4. In a device of the character set forth, a balance wheel having a recessed center portion concentric with its axle, a propeller-shaft disposed across the axis of said wheel, a propeller on said shaft, a longitudinally-movable sleeve on said shaft adapted to rotate with said shaft, a friction roller mounted on said sleeve and rotatable therewith, said roller adapted to bear upon the face of said balance wheel and receive rotatable movement therefrom, means to longitudinally move said sleeve on said propeller shaft and move said roller into and out of engagement with said balance wheel, as and for the purpose set forth.

5. In a device of the character set forth, the combination of a balance wheel having a beveled race on one side thereof, a bevel roller mounted to bear on said race, said wheel on its opposite side being formed with a flat surface and having a central concentric dished cavity, a propeller shaft disposed across the axis of said wheel, a propeller on said shaft, a longitudinally-movable sleeve on said shaft, a friction roller affixed on said sleeve, said roller adapted to bear upon the face of said wheel and to receive motion therefrom and be at neutral when moved into the dished cavity of said wheel, means to rotatably move said sleeve with said shaft, and means to longitudinally move said sleeve on said shaft, substantially as and for the purpose set forth.

6. In a device of the character set forth, the combination with a chassis, supporting members extending above said chassis, a propeller shaft carrying a propeller journaled in said supporting members, a balance wheel journaled to roll transversely to the plane of said propeller and edgewise to the path of flight of said machine, means to rotate said balance wheel, means to impart motion to said propeller from said balance wheel, and means to rotate said balance wheel independent of said propeller shaft.

ARTHUR W. HERRICK.
